COUNTERWEIGHTED PARALLEL MOTION ARM

Charles Henry Little, Cleveland Heights, and
Charles Hubbard Little, Cleveland, Ohio

Application September 22, 1944, Serial No. 555,270

12 Claims. (Cl. 33—79)

1

The present invention relates to drafting machines and similar devices comprising a parallel motion mechanism or arm, one end of which is secured to or is adapted to be secured to a table, drafting board or like device, affording a working surface over which the free end of the arm provided with some suitable instrument is adapted to be moved and the instrument carried thereby maintained parallel in successive positions.

Where the working surface is inclined, the parallel motion arm, which usually comprises two relatively movable sections, will not remain in any predetermined position without being held therein by the operator. In an attempt to overcome this difficulty, various counterpoise mechanisms employing weights as the counterpoise force producing means have been proposed but none of the counterpoise mechanisms heretofore employed have been entirely satisfactory for various reasons, such as, that they give the machine a bulky and ungainly appearance, impose limitations upon the otherwise normal range of movement of the parallel motion arm, etc.

One of the principal objects of the present invention is the provision of a novel and improved drafting machine or similar device, including a parallel motion arm and weight-actuated counterpoise mechanism, which machine is so constructed and arranged that it will not have the appearance of being bulky and ungainly, and the counterpoise mechanism will not interfere with the otherwise normal range of movement of the parallel motion arm.

Another object of the invention is the provision of a novel and improved drafting machine or similar device comprising a wheel and band type parallel motion arm and counterpoise mechanism therefor including a gravity-actuated weight located underneath the working surface or drafting board.

Another object of the invention is the provision of a novel and improved drafting machine or like device comprising a wheel and band type parallel motion arm and weight-operated counterpoise mechanism therefor effective to balance the parallel motion arm at all board angles from zero to ninety degrees.

Another object of the invention is the provision of a novel and improved drafting machine or like device comprising a parallel motion arm and counterpoise mechanism therefor, which counterpoise mechanism is automatically operable for different board angles.

Another object of the invention is the provision of a novel and improved drafting machine or

2

similar device comprising a wheel and band type parallel motion arm and counterpoise mechanism therefor including a weight adapted to be located at the side of the drafting board or working surface opposite to said arm and operatively connected to said arm by means permitting adjustment of said weight angularly with respect to the arm.

The invention resides in certain constructions 10 and combinations and arrangements of parts and further objects and advantages will be apparent to those skilled in the art to which it relates from the following description of the preferred embodiment with reference to the accompanying drawings forming a part of this specification in which similar reference characters designate corresponding parts, and in which

Fig. 1 is a front view of a drafting machine embodying the present invention attached to a vertical drafting board;

Fig. 2 is a fragmentary sectional view, with portions in elevation, of the device shown in Fig. 1, approximately on the line 2—2 of Fig. 1, with both sections of the parallel motion arm positioned at right angles to the upper edge of the drawing board; and

Fig. 3 is a fragmentary rear view of the device shown in Fig. 1, with the various parts in the positions shown in Fig. 2.

30 The drafting machine shown comprises a jointed two-section parallel motion mechanism or arm of the wheel and band type having an instrument or protractor head A at one end and the other end fixedly secured, as by wood screws 10, 35 to a vertical drafting board B. The instrument head A is adapted to be moved about the working surface of the drawing board B and the rulers or other instruments forming a part thereof maintained parallel by the parallel motion mechanism in successive positions to which they are moved.

The parallel motion mechanism or arm shown, which is the preferred construction, comprises two angularly movable sections, each comprising 45 a pair of wheels of equal diameter encircled by a flexible band and held in spaced relation with the band under tension by a strut so constructed as to enclose the band and wheels. The upper or anchor section of the parallel motion mechanism 50 or arm comprises the wheels 11 and 12 encircled by an endless band 13 and held in spaced relation by a strut C comprising yokes or yoke members 14 and 15 connected by tubular side members 16 and 17. The upper yoke 14 is pivotally connected to the anchor assembly D, of which the

upper wheel 11 is a part and through the medium of which the parallel motion arm is connected to the drawing board B by being fixedly secured to the front or left-hand end of an elongated bolt or spindle 18 rotatably supported in the anchor bracket by anti-friction bearings 20 and 21, 22 and 23 adjacent to the front, intermediate and rear parts thereof, respectively. The anchor bracket D is made in two parts 24, 25 to facilitate assembly of the various bearings and other parts. The endless band 13 is separable with the ends thereof detachably connected together to facilitate assembly and replacement thereof. The tubular side members of the strut C are preferably similar to those disclosed and claimed in our copending application Serial No. 631,334, filed November 28, 1945, and are separable intermediate their ends with the adjacent portions thereof connected together by tube-like nut members 26 rotatable in one direction to expand the strut and tense the band and in the opposite direction to release the same so that they can be moved along the side members to expose a portion or portions of the band.

The protractor section of the parallel motion arm is of similar construction and comprises equal diameter wheels 30 and 31 encircled by an endless band 32 and held in spaced relation by a strut comprising yoke members 33, 34 connected by tubular side members 35, 36 including tubular nut members similar to the tubular nut members previously referred to. The wheels 12 and 30 at the elbow of the arm are preferably formed integral and are operatively connected to the respective struts by anti-friction bearings 37, 38, respectively. The wheel 31 located at the free end of the parallel motion arm forms a part of the instrument head A. The construction of the protractor strut is such that it encloses the wheels and band of the protractor section.

The instrument or protractor head proper, designated generally as A is similar in construction to that disclosed and claimed in our copending application Serial No. 555,268, filed September 22, 1944, entitled Drafting machine, and is not herein shown and described in detail. Reference is made to the aforesaid application for a complete disclosure thereof. Suffice it to say that the instrument head A comprises a ruler assembly F including a normally rotatable member 40 forming one element of the protractor proper and one or more rulers 41 detachably secured to a ruler or chuck arm 42. In addition, the instrument head comprises a normally stationary protractor element 43 which cooperates with the rotatable protractor element 40 to indicate the angular position of the ruler or rulers, index mechanism including the thumb piece 44, a protractor clamp 45, and a ruler assembly clamp 46.

The counterpoise mechanism shown comprises a pair of counterpoise weights or weight members 50, 51 located at the side of the drawing board B opposite the parallel motion arm and formed integral with pulley wheels 52, 53 rotatably supported by anti-friction bearings 54, 55 upon a bolt 56 fixed in a bracket 57 secured by wood screws 58 to the rear of underside of the drawing board B adjacent to the middle thereof so as not to unduly affect the balance of the board. The pulley wheels 52, 53 are operatively connected to pulley wheels 60, 61 by flexible members or cables 62, 63 comprising turnbuckles 64 of which there is one in each of the two reaches in each cable for tensioning the same.

The rear or lower pulley or wheel 60 which 75

forms a part of the counterpoise mechanism for the anchor section of the parallel motion arm is keyed or otherwise non-rotatably fixed to the bolt 18 adjacent to its rear end and the pulley or wheel 61 which forms a part of the counterpoise mechanism for the protractor or instrument section of the parallel motion arm is rotatably supported on the bolt 18 by an anti-friction bearing 10.

The pulley 61 is operatively connected to the strut of the instrument or lower section of the arm by an internal gear 71 fixed to the front face or side of the pulley 61. The gear and pulley are concentric with the bolt 18 and the gear is continuously in mesh with a pinion 72 fixed to the lower end of a shaft 73 rotatably supported in the bracket D by anti-friction bearings 74, 75. The upper or left-hand end of the shaft 73 is provided with a pinion 76 continuously in mesh with an internal gear 77 fixed to the lower or right-hand side of a pulley 78 rotatably supported on the upper member 25 of the bracket D by an anti-friction bearing 80. The pulley 78 is operatively connected to an equal diameter pulley 81 formed integral with or attached to the upper side of the yoke member 33 of the instrument strut by a flexible member or cable 82 extending around both pulleys and provided with a turnbuckle 83 for tensioning the same. Any rotation of the instrument section of the parallel motion arm relative to the drafting board or any force tending to rotate the same is transmitted by the cable 82, pulley 78, etc., to the pulley 61 and from the pulley 61 to the weight 51 by the flexible member 63.

35 The effective weight of the counterpoise weight members 50, 51 may be adjusted, if desired, in any suitable manner. As shown, the weight members 50, 51 include supplemental members 84, 85, slidable upon rods 86, 87 fixed to the members 50, 51, respectively. The supplemental members 84, 85 are adapted to be secured to the rods 86, 87 in any adjusted position by set screws or the like. If desired, a supplemental bracket or base 88 may be connected to the lower or rear side of the anchor bracket D and to the lower or rear end of the bolt 56 for the purpose of relieving the drafting board B of some, if not all, of the strain produced therein by the tension of the cables 62, 63.

50 The flexible members or cables 62, 63, as shown, encircle the pulley wheels 52, 60 and 53, 61, respectively, and are preferably connected to the wheels by screws 89. This construction reduces the amount of tension which would otherwise be required to prevent the wheels from slipping with respect to the cables. If more rotation is desired than that permitted by the construction shown, it will be obvious that the cables may be looped about the pulleys a greater number of times or the connection 89 therebetween and the pulleys omitted.

55 The two turnbuckles employed in each of the cables 62, 63 are for the purpose of tensioning the cables and permitting the weights to be angularly adjusted slightly with respect to the sections of the parallel motion arm with which they are associated. It will be apparent that if only one turnbuckle was employed, the angular relationship between the weights and the arm would be disturbed every time that the cables were tightened. Alternatively, other means may be employed for adjusting the angularity of the weights with respect to the arm, for example, provision may be made for adjusting the weights relative 70 to the pulleys 52, 53, the pulley 60 relative to the

spindle 18, or the pulley 61 relative to the pulley 18.

It is believed that the operation of the device will be apparent from the foregoing description thereof. Briefly, when the parallel motion arm is positioned at right angles to the upper edge of the drawing board, the center of gravity of the counterpoise weights is directly between the bolts 18, 56, and the weights do not tend to rotate the parallel motion arm. As the arm or either section thereof is moved out of the aforesaid position, the center of gravity of the weight connected to the section is moved to one side or the other of the line connecting the bolts 18 and 56, depending upon which way the section is moved, with the result that the weight or weights balance or counterpoise the parallel motion arm. It is also to be noted that the counterpoising effect of the weights varies as the board angle is changed, the result of which is that the counterpoise mechanism is operable for all board angles without attention on the part of the operator or, in other words, is automatically operable for different board angles.

From the foregoing description of the preferred embodiments of the invention, it will be apparent that the objects heretofore enumerated and others have been accomplished and that a novel and improved drafting machine or like device has been provided comprising counterpoise mechanism of improved design and construction, which counterpoise mechanism does not interfere with the otherwise full movement of the parallel motion arm, does not give the device a bulky and ungainly appearance, is out of the way of the operator, and is effective throughout the range of movement of the parallel motion arm and for all different board angles.

While the preferred embodiments of the invention have been described with considerable detail, the invention is not limited to the particular construction shown and it is our intention to hereby cover all adaptations, modifications and uses thereof which come within the practice of those skilled in the art to which the invention relates and within the spirit and scope of the appended claims.

Having thus described our invention, what we claim is:

1. In a drafting machine or like device including a multi-section, parallel motion mechanism or arm of the wheel and band type adapted to have connected one end thereof to a drawing board or the like, counterpoise means for a section of the parallel motion arm comprising a weight adapted to be pivotally supported at the side of the drawing board opposite the parallel motion arm for rotation at a constant predetermined radius about an axis at right angles to the working surface of the drawing board, and means for operatively connecting said weight to a section of said arm.

2. In a drafting machine or like device including a multi-section, wheel and band type, parallel motion mechanism or arm adapted to have one end thereof connected to a drawing board or the like, a weight for counterpoising a section of said arm, means adapted for pivotally supporting said weight at the side of the drawing board opposite said arm for rotation at a constant radius about a fixed axis, means including two relatively rotatable members for operatively connecting said weight to the section of said parallel motion arm to be balanced thereby, and

means for adjusting said members angularly relative to each other.

3. In a drafting machine or like device including a multi-section, parallel motion mechanism or arm adapted to have one end thereof connected to a drawing board or the like, counterpoise means for each section of said parallel motion arm so constructed as to permit rotation of said arm through substantially 360° and comprising counterpoise force producing mechanism including a plurality of weights pivotally supported at the side of said drawing board opposite the parallel motion arm for rotation at a constant radius about a fixed axis, and means for connecting said weight to said arm.

4. In a drafting machine or like device including a multi-section, parallel motion mechanism or arm adapted to have one end thereof connected to a drawing board or the like, means for counterpoising the section of said parallel motion arm at the free end thereof when it projects to either side of the longitudinal center line of the section to which it is connected, said means comprising a weight pivotally supported at the side of said drawing board opposite the parallel motion arm for rotation at a constant radius about an axis at right angles to the working surface of said drawing board, and means for connecting said weight to the arm.

5. In a drafting machine or like device including a parallel motion mechanism or arm adapted to be connected to a drawing board or the like for movement over at least a portion of one side thereof, a weight for counterbalancing said arm, said weight being adapted to be pivotally connected to the side of said drawing board opposite the parallel motion arm and adjacent to the center thereof for rotation at a constant predetermined radius about an axis at right angles to the working surface of the drawing board, and means for operatively connecting said weight to said parallel motion mechanism.

6. In a drafting machine or like device a parallel motion mechanism or arm adapted to be connected to a drawing board or the like for movement over at least a portion of one side thereof, a weight pivotally supported at the side of said drawing board opposite the parallel motion arm for counterbalancing said arm, and means including internal gears located at opposite sides of the drawing board and connected by a shaft provided with pinions meshing with said gears for operatively connecting said weight to said arm.

7. In a drafting machine or like device a parallel motion mechanism or arm adapted to be connected to a drawing board or the like for movement over at least a portion of one side thereof, a weight adapted to be pivotally connected to the side of said drawing board opposite the parallel motion arm for counterbalancing said arm, and means including a pair of wheels encircled by a flexible member for operatively connecting said weight to said parallel motion arm.

8. In a drafting machine or like device a parallel motion mechanism or arm adapted to be connected to a drawing board or the like for movement over at least a portion of one side thereof, a weight adapted to be pivotally connected to the side of said drawing board opposite the parallel motion mechanism for counterbalancing said arm, a spindle extending to opposite sides of said drawing board, means for operatively connecting one end of said spindle with said parallel motion arm, and means including a pair of wheels en-

circled by a flexible member for operatively connecting said weight to the opposite end of said spindle.

9. In a drafting machine or like device including a multi-section, parallel motion mechanism or arm having an instrument adjacent to one end thereof and means adapted to connect the other end of said arm to a drawing board or the like, a weight adapted to be pivotally connected to the side of said drawing board opposite the parallel motion mechanism for counterbalancing the section of said arm at the free end thereof, a spindle extending to opposite sides of said drawing board, pinions on opposite ends of said spindle, an internal gear in mesh with said pinion adjacent to said arm, means comprising a pair of wheels encircled by a flexible member for operatively connecting said internal gear to said section, an internal gear in mesh with the other of said pinions, and means including a pair of wheels encircled by a flexible member for operatively connecting said weight to said last-named internal gear.

10. In a drafting machine or like device adapted to be used on an inclined drawing board or the like, an anchor member adapted to be connected to a drawing board or the like, a wheel fixed with respect to said anchor member and adapted to be located at one side of the drawing board to which the anchor member is attached, a strut rotatably supported concentric with said wheel, a second wheel spaced from said first wheel, means for pivotally connecting said second wheel to said strut, a flexible band encircling said wheels, a third wheel concentric with said second wheel and fixed with respect thereto, a second strut, means for pivotally connecting said second strut to said third wheel for rotation about an axis concentric therewith, a member located adjacent to said first wheel, means for supporting said member for rotation about an axis concentric with the axis of said first strut, means for operatively connecting said member with said second strut, a weight for counterpoising said second strut and adapted to be located at the side of the drawing board opposite said wheels, and means for operatively connecting said weight to said member.

11. In a drafting machine or like device adapted to be used on an inclined drawing board or the like, an anchor member adapted to be connected to a drawing board or the like, a wheel fixed with respect to said anchor member and adapted to be located at one side of the drawing board to which the anchor member is attached, a strut rotatably supported concentric with said wheel, a second wheel spaced from said first wheel, means for pivotally connecting said second wheel to said strut, a flexible band encircling said wheels, a third wheel concentric with said second wheel and fixed with respect thereto, a second strut, means for pivotally connecting said second strut to said third wheel for rotation about

an axis concentric therewith, a fourth wheel located adjacent to said first wheel, means for supporting said fourth wheel for rotation about an axis concentric with the axis of said first strut, a fifth wheel concentric with said second and third wheels and fixed to said second strut, a flexible band encircling said fourth and fifth wheels, a weight for counterpoising said second strut and adapted to be located at the side of the drawing board opposite said wheels, and means for operatively connecting said weight to said fourth wheel.

12. In a drafting machine or like device adapted to be used on an inclined drawing board or the like, an anchor member adapted to be connected to a drawing board or the like, a wheel fixed with respect to said anchor member and adapted to be located at one side of the drawing board to which the anchor member is attached, a spindle rotatably supported in said anchor member concentric with said wheel and adapted to extend to opposite sides of the drawing board, a strut fixed with respect to said spindle, a second wheel spaced from said first wheel, means for pivotally connecting said second wheel to said strut, a flexible band encircling said wheels, a weight adapted to be located at the side of said drawing board opposite said wheels, means for operatively connecting said weight to said spindle, a third wheel concentric with said second wheel and fixed with respect thereto, a second strut, means for pivotally connecting said second strut to said third wheel for rotation about an axis concentric therewith, a fourth wheel spaced from said third wheel, means for pivotally connecting said fourth wheel to said second strut, a flexible band encircling said third and fourth wheels, a fifth wheel located adjacent to said first wheel, means for supporting said fifth wheel for rotation about an axis concentric with the axis of said spindle, a sixth wheel concentric with said second and third wheels and fixed to said second strut, a flexible band encircling said fifth and sixth wheels, a second weight located adjacent to said first strut, and means for operatively connecting said second weight to said fifth wheel.
